MACHINE TO ATTACH BINDING TO PLATE FORMS AND INNERSOLES OF SHOES

Agenor Eugene St. Germain, Haverhill, Mass.

Application September 9, 1948, Serial No. 48,406

4 Claims. (Cl. 12—24.5)

1

This invention relates to apparatus for use in the manufacture of shoes and more especially to an improved apparatus for applying a finish or wrapper strip to the peripheral edge of a bottom member such as the forepart of a platform or inner sole.

In the manufacture of the type of shoe in which the platform or insole extends only to about the ball and is there attached in overlapping relation to the forward edge of a wedge heel, the platform or insole is usually covered with a wrapper strip independently of the heel wedge, the wrapper extending continuously along the edge from the ball line at one side around the tip of the toe to the ball line on the opposite side, the ends of the wrapper being curved inwardly at the ball line so as to be concealed in the completed shoe. Ordinarily the covering is done by hand, the operator placing one end of a cover strip to which adhesive has been applied against the edge of the platform or insole at or near the ball line, and progressively laying it about the entire periphery to the opposite ball line. Because of inexpert workmanship and carelessness, the wrapper strip is frequently not applied straight, has wrinkles in it, and is not sufficiently taut. Moreover, because the operator's hands are in constant contact with the strip, impressing it in place, adhesive and dirt is transferred to the work so that it becomes soiled and requires cleaning.

The principal objects of this invention are to provide an apparatus which will apply the wrapper strip to the platform or insole with a minimum of handling, rapidly, tautly and free of wrinkles. Other objects are to provide an apparatus which will be semi-automatic in that once the parts have been placed together in the apparatus, the wrapper will be applied to the edge of the insole or platform continuously and progressively throughout the entire periphery without further manual manipulation of the parts. A still further object of the invention is to provide apparatus which will be adapted to handle platforms and insoles of different thicknesses, is compact, durable, and requires little skill in its operation or upkeep.

As herein illustrated, the apparatus has work holding and clamping means arranged to receive a work piece, for example the forepart of an insole or platform minus the shank and heel parts for rotation in a plane parallel to its surfaces about a given axis and an applicator adjacent to the holding and clamping means yieldably urged toward the work holding and clamping

2

means for pressing it against the peripheral edge of the work piece. The applicator is free to turn as the edge travels in engagement with the applicator, and is free to move linearly along a radial path with respect to the axis of rotation of the holding and gripping means as the edge of the work contacting the applicator becomes more or less distant from its center of rotation during rotation. The applicator is in the form of a cylindrical drum having a cylindrical surface for contact with the edge of the work, and extending radially from the cylindrical surface are peripheral spaced projections or flanges having opposed surfaces for engagement with the marginal portion of the work adjacent the edge. One of the projections is fixed, for example is integral with the cylinder, while the other is in the form of an annulus slideable on the cylinder to and from the fixed projection so that the distance therebetween may be varied, and there is means for yieldably fixing the movable projection at any given point with reference to the fixed projection. The applicator is mounted for radial movement on a slide and there is treadle operated linkage for drawing the slide and hence the applicator, to an out-of-the-way position. The holding and gripping means is in the form of a pair of aligned shafts or staffs, the opposed ends of which are spaced and have fixed thereto heads adapted to engage the opposite surfaces of the work. One of the shafts is driven and the heads have teeth projecting therefrom which bite into the work. The other shaft is yieldable, being urged toward the first shaft to hold the toothed heads against the work. The head on the spring-pressed shaft is free to turn about the axis of rotation of the shaft and has but one tooth thereon, this being located at the axis of rotation of the shaft so that rotation is imparted to the work through one shaft without imparting rotation to the other shaft. The driven shaft is adjustable to bring the head carried thereby substantially into the plane of the work-engaging surface of the adjustable projection on the applicator.

Figure 1 is an elevational view of the apparatus forming the invention, portions being shown in section to illustrate details of construction;

Figure 2 is a plan view of the apparatus shown in Figure 1;

Figure 3 is a sectional view taken substantially on the line 3—3 of Figure 1 and in the direction of the arrows;

Figure 4 is a diametral sectional view of the applicator;

Figure 5 is a plan view of a portion of the means for folding the wrapper into engagement with the marginal edge of the workpiece partially in section to illustrate the details of construction;

Figure 6 is a sectional view showing the structure of the means for mounting a work piece; and

Figure 7 is a schematic view illustrating the path of movement of the work piece and applicator.

The apparatus illustrated herein is designed especially to apply a binding in the form of a wrapper strip which has an adhesive coated surface to the foreparts of insoles or platform soles, although it is to be understood that it may be utilized to apply bindings to other analogous articles, provided they are of such size and shape that they may be operated upon.

Referring to the drawings, particularly Fig. 1, the apparatus has a frame 10 schematically shown for supporting the various components in operating relation, consisting of substantially horizontally arranged, vertically spaced frame members 10a, 10b, 10c and 10d rigidly joined in suitable fashion to provide a stable structure for bolting to a table or even to the floor. It is to be understood, however, that any type of frame may be employed. Insofar as the present apparatus is concerned, the type of frame to be employed may be left entirely within the prerogative of the manufacturer.

The frame member 10a is provided with a sleeve 12 therein and spaced members 14 and 16 which are shown as being parallel to each other and connected by a cross member 18. Mounted in the sleeve and through the cross member is an axially adjustable shaft 20 having a keyway 22 therein. The keyway accommodates a pin 24 which fixes a gear 26 thereto. This gear 26 is enmeshed with a worm-type gear 28 which is secured to a shaft 30. The said shaft 30 may have a pulley 32 or other suitable driving means connected therewith. A belt 34 entrained on the pulley provides means for driving the shaft 30. This, of course, rotates the worm 28, which in turn, imparts rotation to the gear 26 and hence to the shaft 20.

A pair of adjustably mounted collars 36 and 38, respectively, are attached to the shaft 20 at spaced points, with a spacing sleeve or thrust bearing 40 therebetween. It is readily apparent that by manipulation of the set screws 42 the shaft 20 may be raised and lowered with relation to the sleeve 40. Accompanying the described structure in order to perform this adjustment is a relatively large set screw 48 which is received in a suitable threaded aperture in the frame member 10b and which bears against the thrust bearing or spacing sleeve 40. It is appreciated that the set screw 48 must also be operated properly in order to raise and lower the said shaft 20 effectively.

At the lower end of the shaft 20 is a head 50 having a set screw 52 therein, thereby detachably mounting the head on the end of the shaft 20. This head is supplied with a number of teeth 56 at the lower surface thereof adapted to clampingly engage a work piece 58. Thus, it is appreciated that if it is desired to remove the head 50 for one reason or another such as to supply a different type of teeth 56 for engagement with a different kind of work 58, this may be easily effected.

It is seen now that the upper surface of a work piece 58 may be clampingly engaged and driven

by means of a power supply, not shown, through the intermediate structure including the shaft and the adjustable mechanism. In order to support the lower surface of the work for rotation and in order that sufficient flexibility may be supplied, a driven shaft 60 is mounted for axial movement in the frame members 10d and 10c. The shaft 60 has an enlarged end 62 (see Figure 6) with an annular recess (unnumbered) therein accommodating a number of anti-friction ball type bearings 64. A plate 66, actually composed of two members welded or otherwise rigidly secured together, is supplied with a similar annular recess, the recess resting on the top of the said balls 64. A housing 68 is disposed around the enlargement 62 and the plate 66 and is fixed to the driven shaft 60 by means of a set screw 69 (see Figure 1).

The plate 66 is formed with a central spur 20 or tooth 70 at the top portion thereof adapted to clampingly engage a work piece 58. Obviously, the shaft 20 which is driven by an outside source transfers its torque to the driven shaft 60.

The driven shaft 60 is mounted for limited 25 vertical movement in the frame members 10c and 10d by resilient means seen best in Figure 1. This resilient means includes an externally threaded sleeve 72 which is threadedly received in a suitable threaded opening provided in the frame member 10d. For manipulation, a hand wheel or the like 76 may be supplied in fixed relation thereto. This sleeve has a bore therein with the driven shaft 60 passing therethrough. A spring 78 or other suitable equivalent resilient biasing means is seated on the said externally threaded sleeve 72 and bearing against a collar 80 having a set screw 82 therein, mounted for axial adjustment of the shaft 60. It is readily appreciated that the efficacy of the spring 78 may be selectively regulated by manipulation of the hand wheel 76, thereby adjusting the effective length and, therefore, the potential energy stored in the spring 78. Thus, the shaft 60 and its appurtenant spur or tooth 70 is constantly pressed 45 in the work piece 58.

An applicator generally indicated at 90 is mounted for sliding movement perpendicular to the longitudinal axis of the shaft 20 and the driven shaft 60 and radially thereof. Referring 50 to Figure 3 it will be seen that the preferred means of mounting said applicator is by a dovetail construction. A pair of blocks 92 and 94, respectively, are attached to a frame member 96 by means of screws 98 or the like. These screws 55 retain the blocks 92 and 94 in alignment and the beveled inside surfaces thereof retain the sliding block 100 in a prescribed path of movement. No lateral movement of the block with relation to the members 92 and 94 is permitted which would be detrimental in the operation of the apparatus. 60 However, sliding movement is permitted and due to the disposition of the members 92 and 94, this sliding movement is substantially normal or perpendicular to the axes of the shafts 20 and 60.

A central spindle 104 (Fig. 4) extends through a drum 106 forming a portion of the applicator and is mounted at one end by means of a bracket 108 which is attached to the sliding block 100. At the opposite end of the spindle 104 there is an 70 opening provided for the pin 110 and incidentally, this pin serves the function of mounting a link 112 for pivotal movement. An end of the link has a spring 114 attached thereto which is also attached to the frame member 10c. This 75 spring is used to constantly urge the spindle 104

and hence the drum 106 toward the work holding means. Thrust bearings 115 and 116 are mounted on the spindle at the opposite ends of the drum. The spindle 104 is made fast in the bracket by screws 118 and 120 which permit adjustment of the spindle to center the same in the bracket.

Means for retracting the applicator from the work holding means is supplied. This means consists of a crank 122 which is mounted for rotation on a rocker shaft 124 supported by the frame member 10d. One end of the crank 122 is attached to the link 112, while the opposite end thereof has a pitman 126 mounted thereon. This pitman extends through the frame member 10d which carries the perches 130 for the said rocker shaft 124 and has an actuating lever 136 pivotally attached at the opposite end thereof. This actuating lever may be either foot operated or hand operated, preferably foot operated.

A shock absorber in the form of a spring 140 reacting on the frame member 10d to the intermediate structure of a thrust collar 142 is supplied. An adjustable collar 144 has the spring 140 seated thereon in order to adjust the effective compressed force thereof.

Referring to Fig. 4, it will be seen that the drum has at its lower end a radially extending projection or flange 150 peripherally thereof, which is illustrated as being integral with the drum. The radially projecting flange has a flat annular surface 151 situated in a plane substantially normal to the axis of the drum, that is at right angles to the cylindrical surface of the drum, and a flat, downwardly inclined, beveled surface 152.

The drum has on it a second peripheral, radially extending projection or flange 160 which is in the form of an annulus slidable on the cylindrical surface of the drum to and from the projecting flange 150 and corresponds in shape thereto, having a flat annular surface 161 parallel to the surface 151 and a beveled surface 162 opposite in inclination to the beveled surface 152. The annulus 160 is adjustably and yieldably supported on the drum so as to vary the space between their cooperating annular surfaces 151 and 161 in accordance with the thickness of the work to be operated upon by a collar 154 surrounding the drum. The collar 154 has a number of screws 156 (Fig. 5) radially positioned therein for contact with the drum 106 and hence for locking the collar at any predetermined position. The drum may have a series of holes in its cylindrical surface for accommodation of the inner ends of the screws 156 or the ends of the screws may frictionally engage the drum. The annulus 160 is yieldably supported by the collar 154 by bolts 158 passing freely through holes arranged around the collar, their heads resting on the upper side of the collar and their ends being threaded into the annulus. A plurality of compression springs 162 are interposed between the collar and annulus, being placed about the bolts and having their ends seated in wells or recesses 166 formed in the collar and annulus. The springs 162 yieldably urge the annulus constituting the projection 160 in a direction toward the projection 150 so that work placed between the projections will be acted upon by yielding pressure.

The apparatus is used in the following manner. A flat strip of binding or wrapping material precut so as to be long enough to extend all the

way around the peripheral edge of an insole or platform, that is the forepart portion thereof, having adhesive applied to one surface, that is the flesh surface, is applied to the insole or platform at about the ball line at one end thereof by sticking an end of the wrapper to the edge of the insole and pinching the margins at that end into engagement with the top and bottom surfaces of the insole which is beveled at the ball line whereupon it is ready to be placed in the apparatus. Prior to placing the work between the work holding and gripping means, the projection 160 should be adjusted to a position on the drum so that the space between its annular surface 161 and the surface 151 of the projection 150 is substantially equal to the thickness of the work. When the projection 160 has been fixed in position, the head 50 may then be adjusted to bring its end face substantially in the plane of the surface 161. Since the applicator in its normal position is yieldably pressed toward the work holding and gripping means, the space between its surface and the holding and gripping means will usually be less than the shortest distance between the edge of the platform or insole and its center, hence the lever 136 must be actuated to retract the applicator to permit introduction of the work between the work holding and gripping means. When the applicator has been retracted, the work is introduced between the toothed heads 50 and 66 of the work holding means by separating the shafts 20 and 60, this being effected by drawing the shaft 60 downwardly against the spring presser of the spring 76. Suitable treadle operated linkage may be provided for this purpose. The work is now placed between the heads 50 and 66, preferably so as to be substantially at the geometrical center thereof, but not necessarily so, the head 66 is allowed to rise against the work, and pinch it between the heads so that the teeth penetrate into the work and then the applicator is allowed to move toward the left as shown in Fig. 1, to engage the edge of the work. While as described, the foregoing steps are performed successively, in actual practice, the machine is in continuous operation and except for adjustment of the parts, the introduction of the work to the holding and gripping means and placing of the applicator against the edge is done so rapidly and so nearly simultaneously that it is not necessary to have a clutch for stopping and starting the machine for each successive operation. In fact, in many instances if the work is stiff and the wrapper not too tender, the work may be placed between the heads against the applicator at the ball end which is the narrower part of the insole, without retracting the applicator and allowed to turn against the applicator. The force pressing the applicator toward the work is sufficient to cause the edge to enter the groove defined by the flanges 150 and 160 so as to bear against the cylindrical surface of the applicator and bend the margins of the wrapper into contact with the top and bottom surfaces of the work. Since the work holding and clamping means is rotating constantly, just as soon as the work is placed therebetween and the applicator allowed to come to rest against its edge, or is forced thereagainst as just described, the wrapper which is anchored at one end to the work, is progressively applied to its edge as the latter turns with reference to the applicator. During this period, the operator holds the free end of the wrapper so that it is in a substantially hori-

zontal position with its flat surface in a vertical plane. The cylindrical surface of the applicator presses the mid-portion of the strip against the edge of the platform and the projections 150 and 160 and at the same time, fold the marginal edges over the top and bottom surfaces of the midsole adjacent to the margins. The yieldable nature of the projection 160 permits the projection to yield sufficiently to accommodate the added thickness of the wrapper strip as it is folded over the edge of the insole and at the same time, presses the wrapper into firm engagement therewith.

The applicator rotates and moves to and from the gripping and holding means in accordance with the distance of the edge of the sole at any time with reference to the center of rotation, and the beveled edges of the projections facilitate guiding the edge of the work between the parallel surfaces into contact with the cylindrical surface of the applicator, on the fly, that is during continued operation of the machine. The path, that is the movement of the edge of the work with reference to the applicator, and movement of the applicator with reference to the work is illustrated in Fig. 7.

From the foregoing, a clear understanding of the present invention is deemed apparent. However, it is obvious that certain changes may be made without departing from the spirit of the invention. Accordingly, limitation is sought only in accordance with the scope of the following claims.

Having described the invention, what is claimed as new is:

1. An edge binding machine comprising means for gripping and holding a flat article, said gripping and holding means being mounted for rotation about an axis and having work engaging elements which have parallel flat work engaging surfaces, said elements being relatively movable to and from each other, means yieldably urging one element toward the other to grip the article therebetween, means carried by one element to penetrate the article under the pressure of the yieldable means, a single applicator adjacent to said gripping and holding means for engagement with the peripheral edge of the article at only one point at any given time, means for supporting said applicator for free rotation about an axis parallel to the axis of the gripping and holding means, and for free movement radially to and from the axis of rotation of the gripping and holding means, said applicator having a cylindrical surface portion for engagement with the peripheral edge of the article and peripherally spaced, radially extending projections having surfaces for engagement with the marginal portions of the article adjacent the peripheral edge, one of the peripheral radially extending projections being a fixed integral part of the cylindrical portion, the other being an annulus mounted on the cylindrical portion of the applicator and slidable on the cylindrical surface to and from the fixed projection, means for fixing the annulus at any given position with respect to the fixed projection, means for effecting rotation of said gripping and holding means to turn the article held thereby, rotation and radial movement of said applicator being effected through contact of the article therewith, and means for yieldably urging the applicator toward the gripping and holding means to hold it against the edge of the article during rotation thereof.

2. An edge binding machine comprising means for gripping and holding a flat article, said gripping and holding means being mounted for rotation about an axis and having work engaging elements which have parallel flat work engaging surfaces, said elements being relatively movable to and from each other, means yieldably urging one element toward the other to grip the article therebetween, means carried by one element to penetrate the article under the pressure of the yieldable means, a single applicator adjacent to said gripping and holding means for engagement with the peripheral edge of the article at only one point at any given time, means for supporting said applicator for free rotation about an axis parallel to the axis of the gripping and holding means, and for free movement radially to and from the axis of rotation of the gripping and holding means, said applicator having a cylindrical portion for engagement with the peripheral edge of the article and peripherally spaced, radially extending projections having surfaces for engagement with the marginal portions of the article adjacent the peripheral edge, one of the peripheral radial projections being fixed, a collar mounted on the cylindrical portion of the applicator, said collar being movable thereon to and from the fixed projection, means associated with the collar to fix it at any given position on the cylindrical portion of the applicator, the other projection being in the form of an annulus surrounding the cylindrical portion of the applicator yieldably carried by the collar in a position opposite the fixed radial projection, means for effecting rotation of said gripping and holding means to turn the article held thereby, rotation and radial movement of said applicator being effected through contact of the article therewith, and means for yieldably urging the applicator toward the gripping and holding means to hold it against the edge of the article during rotation thereof.
3. An edge binding machine comprising an applicator, means for gripping and holding a flat article for rotation in the plane of its surface to present its edge continuously to said applicator, said applicator having contact with the peripheral edge of the article at only one point at any given time, means for supporting said applicator for free rotation about an axis parallel to the axis of rotation of the gripping and holding means, and for free movement radially to and from the axis of rotation of the gripping and holding means, said applicator having a cylindrical surface portion for engagement with the peripheral edge of the article and peripherally spaced, radially extending projections having surfaces for engagement with the marginal portions of the article adjacent the peripheral edge, said gripping and holding means comprising aligned shafts having spaced, opposed ends, heads fast to said opposed ends for engagement with the opposite sides of the work, means yieldably urging one of the shafts in a direction to cause the heads to grip the work, means for adjusting one of the shafts to bring its head substantially into the plane of the radially extending annular surface portion of one of the projections of the applicator, means for effecting rotation of said gripping and holding means to turn the article held thereby, rotation and radial movement of said applicator being effected through contact of the article therewith, and means for yieldably urging the applicator toward the grip-

ping and holding means to hold it against the edge of the article during rotation thereof.

4. An edge binding machine comprising an applicator, means for gripping and holding a flat article for rotation in the plane of its surface to present its edge continuously to said applicator, said applicator having contact with the peripheral edge of the article at only one point at any given time, means for supporting said applicator for free rotation about an axis parallel to the axis of rotation of the gripping and holding means, and for free movement radially to and from the axis of rotation of the gripping and holding means, said applicator having a cylindrical surface portion for engagement with the peripheral edge of the article and peripherally spaced, radially extending projections having surfaces for engagement with the marginal portions of the article adjacent the peripheral edge, said gripping and holding means comprising aligned 20 shafts having spaced, opposed ends, heads fast to said opposed ends for engagement with the opposite sides of the work, means for adjusting one of the shafts to bring the head substantially to the level of the annular surface of one of the 25 projections on the applicator and means yieldably urging the other shaft toward the adjustable shaft, means for effecting rotation of said grip-

ping and holding means to turn the article held thereby, rotation and radial movement of said applicator being effected through contact of the article therewith, and means for yieldably urging the applicator toward the gripping and holding means to hold it against the edge of the article during rotation thereof.
